UNITED STATES PATENT OFFICE.

MAX KAUFMAN, OF BROOKLYN, NEW YORK.

LADY'S HANDBAG.

1,376,099.

Specification of Letters Patent. Patented Apr. 26, 1921.

Application filed July 31, 1920. Serial No. 400,403.

To all whom it may concern:

Be it known that I, MAX KAUFMAN, a citizen of the United States, and resident of Brooklyn, in the city of New York, county 5 of Kings, and State of New York, have invented certain new and useful Improvements in Ladies' Handbags, of which the following is a specification.

The present invention relates to improvements in ladies' hand bags, and it more particularly refers to a hand bag involving a novel construction of frame by the use of which exterior pockets or pouches of comparatively small dimensions are provided in 10 conjunction with the bag in which to hold articles frequently and habitually used, such as car tickets, without requiring resort to the main bag.

An object of the invention is to provide 20 one or more additional frames supplementing the main frame of a lady's hand bag to which fabric may be stitched or otherwise secured providing in effect a supplemental bag or pouch which lies exteriorly of the 25 main bag so that its contents may be removed without having to open the main frame.

At the present time such articles as car 30 tickets or tokens, small change, powder puffs, mirrors, etc., are generally thrown indiscriminately into the main bag so that confusion is attended with the locating of any of these articles, and this condition is the source of much annoyance to the user 35 of the bag.

It is, consequently, a further object of the 40 invention to provide a lady's hand bag which will avoid this annoyance and confusion and which provides a simple and inexpensive construction of framework to the end of better convenience and greater satisfaction to the user.

With the above and other objects in view, the present invention contemplates the 45 provision of an improved lady's hand bag, above characterized and the novel form, construction, and arrangement of its several parts as will be hereinafter more fully described, illustrated in the accompanying 50 drawing and subsequently incorporated in the subjoined claims.

In the drawing wherein I have illustrated one embodiment of the invention and in which similar reference characters 55 designate corresponding parts throughout the several views,

Figure 1 is a perspective view of an improved lady's hand bag constructed in accordance with the present invention and shown in a closed position. 60

Fig. 2 is a sectional view taken therethrough and showing one of the supplemental pouches or pockets in an open position;

Fig. 3 is a view similar to Fig. 2 with the 65 main frame of the bag open; and

Fig. 4 is a perspective view of one of the supplemental frames detached and in open position.

Referring more particularly to the drawings, 1 designates the fabric of the main bag which is constructed after the present fashion, and 2 and 3 represent the complementary sections of the main bag frame, hingedly connected at their lower ends as indicated 70 at 4. This frame is not unlike the conventional bag frame and comprises the elongated pieces 5 from which depend at opposite ends the pairs of parallel legs 6 and 7.

The lower ends of the legs 6 and 7 are 80 bent together at the hinged joint 4 so that the two sections of the main frame when clasped together give the general appearance of having a rectangular form in which one side of the rectangle is removed, this 85 being filled in by the fabric 1 of the bag.

About the interior edges of the pieces 5 and legs 6 and 7 there are provided perforations 8 in which to receive the threads, 90 stitches, or other fastening means 9 by which the fabric 1 is secured to the main frame. The pieces 5 of the two main frame sections are provided with flanges 10 and 11 which are bent over from the appropriate metal or other material out of which the sections 95 are made, so that the free edges of the flanges abut and form a tight joint.

Similarly the legs of the main frame are supplied with flanges 12 and 13 which form continuations of the flanges 10 and 11 at 100 the sides of the frame and which abut together to produce a tightly inclosed bag.

A clasp 14 of the usual variety has its complementary parts carried respectively by the flanges 10 and 11 and provides for holding 105 the frame closed until a suitable force is applied thereto as by exerting a turning movement on the two members of the clasp by the thumb and forefinger. Obviously, 110 a different form of clasp might be employed.

The bail or handle 15 is shown in the present instance as composed of chain links

having rings 16 and 17 at the ends thereof to engage with keepers 18 and 19 on the flanges 10 and 11.

At the inner edge of one or both of the pieces 5 are formed or attached one or more eyes 20 receiving pintles 21 projecting beyond the intermediate eyes 20 and entering coaxially extending lateral eyes 22 and 23 projecting from one end of a supplemental frame. The ends of the pintles may be upset if desired to secure them against accidental displacement. Each supplemental frame is also preferably, though not necessarily, rectangular in form and is composed of parallel head and base pieces 24 and 25 respectively connected by parallel side rails 26 and 27 which are with advantage stamped or otherwise produced from a single piece of metal.

20 The base pieces 25 are provided with integral or attached eyes 28 designed to carry pintles 29 which also extend through pairs of lateral eyes 30 and 31 received over the ends of the pintles and swinging thereon.

25 The last-mentioned eyes are carried by closure frames 32 which are counterparts of the supplemental frames and are constructed of such dimensions that the closure frames may be slipped within the supplemental frames, as in the manner illustrated in Fig.

30 3. I find it preferable to also make the closure frames of an open or skeleton construction and to both supplemental and closure frames fabric of an appropriate kind is applied in any suitable manner. For instance, both the supplemental and closure frames are perforated and receive the stitching or other fastening means 33 and 34 which passes through the edges of the fabric 35 and 36 employed to inclose the frames.

The fabric is preferably left loose especially in cases where more spacious pouches or pockets are required. Strips or pieces of fabric 37 and 38 are sewed or otherwise secured to the interior portions of the frames so that they provide with the outer fabric 35 and 36 compartments of desired capacities to hold designated articles.

The head pieces 24 of the supplemental frames are supplied with apertures 39 to receive the compressible glove fasteners 40 carried by the free parallel ends of the closure frames 32. Ornamental handles 41 are attached to the fasteners or to the frames through which the user may exert the necessary pressure to remove the heads 40 from the apertures 39.

In use, a hand bag according to the invention presents the general appearance suggested in Fig. 1 where one section of the main frame carries two of the supplemental pouches. This is a preferred construction inasmuch as it affords suitable space in the four compartments thus provided in which to carry articles of general use, the service

of which is frequent and hasty. For instance, one of the compartments of a pouch may contain car tickets or tokens so as to hold them in a place separated from the confused articles in the larger bag body and where they may be extracted without annoyance and difficulty in congested places.

This or a companion pocket may be utilized to hold stamps, while another pocket may receive a watch whereby the latter may be consulted with ease. The pockets of the second pouch may respectively contain a mirror and powder puff. Various other articles whose use is required repeatedly may be segregated in one or more pockets of a supplemental pouch such as I have provided and become thus easy to locate and remove, and avoid the trouble incident to searching through the large bag among numerous confused articles.

85 The hinged connection of the supplemental pouches or frames with the main frame is desirable as suggested in Fig. 3 to permit of the pouches swinging to one side when the main frame is opened, as otherwise the presence of the pouches would be apt to interfere with the proper opening of the main bag or with convenient access to the same. The hinged mounting of the closure frames of the pouches is so arranged and constructed as to reveal a wide space for clearly showing the contents of the pockets and for giving free access for the removal and replacement of the article held therein.

90 I have herein shown and described a practical embodiment of my invention which has been found to be very satisfactory, but it will be understood that the device may also be exemplified in numerous other alternative constructions, and that the size, relative proportions, and construction of its several parts, are also susceptible of considerable modification. Accordingly, I reserve the 95 privilege of resorting to all such legitimate changes as may be fully embodied within the 100 spirit and scope of the appended claims.

105 What is claimed is:

1. A lady's hand bag comprising a main frame openable at its top, a bag body secured to the main frame, a supplemental frame hinged at its top to the side of said main frame, a closure frame hinged at its lower end to the lower end of the supplemental frame and adapted to be swung upwardly thereagainst to provide a receptacle, 115 and independent fastening means for said main and closure frames arranged at the tops thereof, whereby ready and independent access may be had to the interior of the bag body and the receptacle.

120 2. A lady's hand bag comprising an upwardly openable main frame, a bag body suspended therefrom, a supplemental frame hinged at its upper end to the side of said main frame and depending therefrom at the 125 130

outer side of the bag body and adapted to swing outwardly upon the bulging of the bag body, and a closure frame hinged at its lower end to the lower end of the supplemental frame and adapted to swing upwardly thereagainst, said supplemental and closure frames providing a pocket therebetween, and said closure frame being of less dimensions than the supplemental frame whereby the closure frame may fit thereinto and 10 tightly close said pocket.

In testimony that I claim the foregoing as my invention, I have signed my name hereunder.

MAX KAUFMAN.
